UNITED STATES PATENT OFFICE.

WALTER B. WEBER, OF PHILADELPHIA, PENNSYLVANIA, ASSIGNOR TO GEORGE W. SMITH WOOD WORKING COMPANY, OF PHILADELPHIA, PENNSYLVANIA, A CORPORATION OF PENNSYLVANIA.

DESIGN FOR A VALANCE FOR SHOW WINDOWS.

Application filed April 13, 1925. Serial No. 13,107. Term of patent 3½ years.

To all whom it may concern:

Be it known that I, WALTER B. WEBER, a citizen of the United States, residing in Philadelphia, Pennsylvania, have invented a new, original, and ornamental Design for a Valance for Show Windows, of which the following is a specification, reference being had to the accompanying drawing, forming a part thereof, in which:

The single figure of the drawing is an elevational view of a valance embodying my new design.

I claim:

The ornamental design for a valance for show windows, as shown.

WALTER B. WEBER.
